UNITED STATES PATENT OFFICE

136,062

DESIGN FOR A COMBINED CONTAINER AND BASE THEREFOR

Meyer Sosman, Brooklyn, N. Y., assignor to
Glasorb Company, New York, N. Y.

Application November 24, 1942, Serial No. 108,864

Term of patent 7 years

To all whom it may concern:

Be it known that I, Meyer Sosman, a citizen of the United States of America, residing in Brooklyn, in the county of Kings and State of New York, have invented a new, original, and ornamental Design for Combined Container and Base Therefor, of which the following is a specification, reference being had to the accompanying drawing, forming a part thereof and in which:

Fig. 1 is a perspective view of the base portion only of a combined container and base therefor

embodying my new design.

Figure 2 is a side elevational view of the complete article, and

Figure 3 is a top plan view thereof.

The dominant features of my design reside in the portions shown in full lines.

I claim:

The ornamental design for a combined container and base therefor, as shown and described.

MEYER SOSMAN.
